UNITED STATES PATENT OFFICE.

WILLIAM MCINTYRE, OF PENNS GROVE, NEW JERSEY.

WINDOW.

Application filed May 8, 1923. Serial No. 637,453.

To all whom it may concern:

Be it known that I, WILLIAM MCINTYRE, a citizen of the United States, residing at Penns Grove, in the county of Salem and State of New Jersey, have invented certain new and useful Improvements in Windows, of which the following is a specification.

My invention relates to windows, more particularly of the type in which the window sashes slide in the frame and are made up of sections which are hinged so that the sashes may be swung into the building to be cleaned. The object is to provide a window of this type which may be installed without change or alteration in the ordinary window frame, which is easy to install and of a simple and durable construction.

This object, and other advantageous ends which will be described hereinafter, I attain in the following manner, reference being had to the accompanying drawings in which—

Figure 1 is an inside elevation of a window constructed in accordance with my invention,

Figure 2 a view similar to Figure 1 illustrating the window sashes in their open position for cleaning,

Figure 3 a section on line 3—3 of Figure 1,

Figure 4 a section on line 4—4 of Figure 2,

Figure 5 a perspective view illustrating the position of the holder and locking block, 35 and

Figure 6 an enlarged fragmentary section on line 6—6 of Figure 4.

Referring to the drawings, 1 is a window frame having guideways 2 and 3 separated by parting strips 4. A window sash 5 slides in guideway 2 and another sash 6 slides in guideway 3. The sashes 5 and 6 are similarly constructed and I will therefore describe both at the same time and give them similar reference characters.

The sashes are composed of supporting sections 7, main sections 8 and locking sections 9. The supporting sections and the main sections are hinged together at 10. The locking sections and the main sections are locked to each other by any suitable locks 11. Balance ropes 12 are secured to the supporting and locking sections and have balance weights 13 thereon. The sashes 5 and 6 are so mounted that the main sections

8 will swing on their hinges in opposite directions as shown in Figure 4. To hold the supporting sections in the guideways when the main sections are in their open positions, I provide holders 14 consisting of metallic strips having feet 15 formed on one side and secured to the guideways and inwardly bent flanges 16 on the other side embracing the supporting sections as shown in Figures 4 and 5.

When my window is in use and it is desired to clean the same, the window sash 6 is lowered and the main sash sections unlocked from the locking sections and opened into the position shown in Figures 2 and 4. To prevent the balance weight from pulling the locking sections upward, I provide locking blocks 17 hinged to parting strips 4 by hinges 18, the locking blocks being adapted to swing in guideway 2 on one side of the frame and in guideway 3 on the other side and hold the locking sections 9 against upward movement. When the main sashes are in their open position the holders 14, by reason of their inwardly bent flanges, will hold the supporting sections in the guideways. After the windows are cleaned, the main sashes are closed and locked to the locking sections by locks 11 and the locking blocks 17 are swung on their hinges 18 into a position in line with parting strips 4 and forming a part thereof. As an additional means for securing the locking sections to the main section I provide stops 19 on the locking sections at their tops and bottoms. These stops prevent upward and downward displacement of the locking sections relative to the main sections.

The joints or meeting edges of the sash sections are preferably lined with felt 20 to make a tight joint and seal against the weather.

By constructing a sash as above described a window which may be easily and safely cleaned is provided of a simple and durable construction which is easily installed and requires practically no change or alteration in the window frame for its installation.

While I have described my invention as taking a particular form, it will be understood that the various parts of my invention may be changed without departing from the spirit of the invention and hence I do not limit myself to the precise construction set forth but consider that I am

2
at liberty to make such changes and alterations as fairly come within the scope of the appended claims.

Having thus described my invention, what I claim as new and desire to secure by Letters Patent is:

1. A window including a frame having guideways; parting strips between the guideways, and window sash sections slidable in the guideways, each parting strip comprising a horizontally swinging section adapted to be swung from its normal position to a position within one of the guideways to preclude upward movement of the respective sash.

2. A window including a frame having guideways; a supporting sash section slidable in one of the guideways; a locking sash section sliding in the opposite guideway; a main sash section hinged to the supporting section, and a holder secured in said one of the guideways, extending between the

supporting and main sash sections and embracing the supporting section to hold it in the guideway.

25

3. A window including a frame having guideways; a supporting sash section slidable in one of the guideways; a locking sash section sliding in the opposite guideway; a main sash section hinged to the supporting section, and a strip having a foot on one side secured in said one of the guideways and an inwardly bent flange on the other side extending between the supporting and main sash sections and embracing the supporting section to hold it in the guideway.

35

In testimony whereof I have signed my name to this specification in the presence of two subscribing witnesses.

WILLIAM McINTYRE.
